DESIGN FOR A CLOCK CASING

Max E. Schlenker, Peru, Ill., assignor to General
Time Instruments Corporation, New York,
N. Y., a corporation of Delaware

Application March 22, 1941, Serial No. 99,785

Term of patent 7 years

To all whom it may concern:

Be it known that I, Max E. Schlenker, a citizen
of the United States, residing in the city of Peru,
in the county of La Salle and State of Illinois,
have invented a new, original, and ornamental
Design for a Clock Casing, of which the following
is a specification, reference being had to the
accompanying drawing, forming a part thereof.

Figure 1 is a perspective view of the clock cas-
ing showing my new design;

Figure 2 is a front elevational view thereof;
and

Figure 3 is a side elevation thereof, a part of
the cord and plug connection being omitted for
convenience of illustration.

I claim:

The ornamental design for a clock casing, as
shown and described.

MAX E. SCHLENKER.
